DESIGN FOR A CONDIMENT HOLDER

Hugo W. Kruse, Rockford, Ill., assignor to Geo. D. Roper Corporation, Rockford, Ill., a corporation of Illinois

Application April 16, 1941, Serial No. 100,418

Term of patent 7 years

To all whom it may concern:

Be it known that I, Hugo W. Kruse, a citizen of the United States, residing at Rockford, in the county of Winnebago and State of Illinois, have invented a new, original, and ornamental Design for a Condiment Holder, of which the following is a specification, reference being had to the accompanying drawing, forming part thereof.

In the drawing:

Fig. 1 is a front elevational view of a condiment holder, showing my new design;

Fig. 2 is a top plan view; and

Fig. 3 is a perspective view thereof.

In these views the stippled surfaces indicate contrasting color.

I claim:

The ornamental design for a condiment holder, substantially as shown and described.

HUGO W. KRUSE.
